UNITED STATES PATENT OFFICE

2,596,296

COMB

Lavelle W. Shields, Waterbury, Conn.

Application December 16, 1948, Serial No. 65,632

1 Claim. (Cl. 132—18)

1

The present invention relates in general to combs and more especially to a comb having teeth of an improved construction for exercising the hair and scalp.

An object of the invention is to provide a comb having superior teeth for treatment of the hair.

A further object of the invention is to provide a comb with teeth characterized by a curvature which lifts the hair from the scalp thereby exerting a gentle pull on the hair for effectively exercising the roots of the hair and massaging the scalp.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a perspective view of a comb embodying the improved curved teeth of this invention, the comb of Fig. 1 being of the reservoir type for supplying a hair-treating lotion to the curved teeth of the comb;

Fig. 2 is a side elevation partly in section of the reservoir type of comb of Fig. 1;

Fig. 3 is an end elevation of the comb on section line 3—3 of Fig. 2;

Fig. 4 is a perspective view of the back of the comb with the wick removed from the wick-receiving aperture thereof and showing the internally-threaded recess in the end of the comb, for attaching the handle thereto;

Fig. 5 is an end elevation of the back of the comb shown in Fig. 4, illustrating the eccentricity of the fluid-supplying passage of the back of the comb to the handle-receiving recess thereof;

Fig. 6 is a perspective view of a modification of the comb wherein the back and handle of the comb are solid and the teeth have an accentuated curvature;

Fig. 7 is an end elevation of the comb of Fig. 6 showing the accentuated curvature of the teeth of the comb;

Fig. 8 is a perspective view of a further modification of the comb, the comb having a substantially-solid back and handle and being provided with double-ended curved teeth for facilitating use of the comb by either right- or left-handed persons; and

Fig. 9 is an end elevation of the comb of Fig. 8.

The showing of Figs. 1 to 5, inclusive

An exemplary embodiment of the invention is illustrated in Figs. 1 to 5 wherein is shown a comb for exercising and treating the hair and scalp, the comb comprising, in the main, a handle 10 and a back-portion 11, the latter being substantially rectangular in cross section but rounded on its upper edge and formed on its lower edge with curved teeth 12. In this embodiment of the invention, the curved teeth 12 of the comb are adapted to be provided with a suitable liquid for

2

treating the hair, and to this end the back 11 and curved teeth 12 of the comb are molded or similarly formed from a plastic or equivalent material, each tooth constituting a substantially-straight root-portion 13, the base of which is molded integrally with the back-portion of the comb and projects therefrom substantially perpendicular to the longitudinal axis thereof. Each tooth has a curved apex-portion 14 in the vertical plane of its respective root-portion 13 so that the extremity of each tooth projects laterally from the root-portion substantially at right angles thereto for lifting the hair of the scalp. The concave or inner edge of this curved apex-portion of each tooth defines substantially an arc of a circle, while the convex or outer edge of the tooth defines an arc of a different circle eccentric to the first. Each respective tooth is in spaced-parallel relationship to the root-portion of adjacent teeth to provide a slot therebetween for accommodating strands of hair segregated by the root-portions of the teeth in a combing action. The root of each tooth on the side thereof from which its respective apex-portion projects, which side is hereinafter referred to as the "inner wall" of the tooth, is formed with a recess 15 extending transversely thereof. As shown especially well in Figs. 1 and 3, each recess 15 is substantially semicircular in cross section and intersects the opposite sides respectively of the root-portion of each tooth and the bottom edge of the back-portion of the comb, the continuity of the circumferential wall of each recess 15 being broken at its intersection with the inner wall of the root-portion of its respective tooth to form a relatively-narrow opening 16 extending transversely thereof. The recesses 15 of the successive teeth of the comb are aligned axially and constitute a substantially-continuous aperture indicated generally at 17, extending longitudinally of the comb and in communication with the inner walls of the teeth through their respective openings 16. A wick 18 is adapted to be mounted in the longitudinally-extending aperture 17 of the comb, the wick being exposed intermediate each tooth and by the openings 16 thereof to the inner walls of the teeth for bleeding a hair-treating lotion to each individual tooth of the comb, the wick 18 being supplied with the lotion by means of weep-apertures 19.

In the present embodiment, four such weep-apertures are provided substantially equally spaced along the length of the wick, the lower end of each weep-aperture intersecting the upper wall of the longitudinal aperture 17 and the upper end of each weep-aperture intersecting the bottom wall of a liquid-supply passage 20 extending longitudinally through the back-portion of the comb. The forward or outer end of the liquid-supply passage 20 is blind, whereas the inner end of the passage intersects an internally-threaded substantially-circular recess 21 formed in an integral substantially-cylindrical enlargement 22 at the inner end of the back-portion 11 of the

comb, the longitudinal axis of the recess 21 being eccentric to the longitudinal axis of the passage 20, as shown especially well in Fig. 5. The enlargement 22 on the back-portion of the comb constitutes a continuation of the handle 10 which, for the most part, comprises a substantially-cylindrical vessel or bottle 23, the outer diameter of which corresponds to the outer diameter of the enlargement 22 of the comb-back, while the neck of the bottle is provided with external threads adapted to threadedly engage in the internally-threaded recess 22 of the comb-back.

The two parts of the handle are adapted to fit together with a liquid-tight joint so as to preclude the escape of liquid from the bottle. The liquid in the bottle 23 is preferably a hair lotion and is adapted to flow into the longitudinal supply-passage 20 in the back-portion of the comb through the weep-apertures 19 thereof to the wick 18. Thus, when the comb is drawn through the hair, the hair is raised by the curved apices of the teeth adjacent the openings 16 at the root-portions thereof to wipe over the wick, whereby the hair lotion is applied to the hair. Simultaneously with the application of the lotion to the hair, the curved apices of the teeth of the comb lift the hair so as to exert a gentle pull thereon which exercises the scalp and roots of the hair and facilitates straightening snarled and matted hair.

The showing of Figs. 6 and 7

A modification of the curved-tooth comb of this invention is shown in Figs. 6 and 7 in which the comb, indicated generally at 25, is formed of a plastic or equivalent material and comprises a solid handle 26 and a solid back-portion 27 substantially rectangular in cross section, its upper edge being rounded and its lower edge formed with integral curved teeth 28. The handle 26 is substantially circular in cross section and formed integrally with the back-portion of the comb, the longitudinal axis of the handle 26 being eccentric thereto, as shown especially well in Fig. 7. Each tooth 28 of the comb is formed similarly with a root-portion 29 and an apex-portion 30, the longitudinal axis of the root-portion of each tooth being substantially perpendicular to the longitudinal axis of the comb-back 27. In this embodiment of the invention, the curved apex-portion 30 of each tooth is formed substantially on the arc of a relatively-small circle such that the apex-portion of each tooth is offset laterally from and at substantially right angles to its respective root-portion. This increased curvature of the teeth of the comb provides an improved lifting action on the hair and, in particular, thick hair, for exercising the roots thereof and the scalp.

The showing of Figs. 8 and 9

The combs described above and shown in Figs. 1 to 7 inclusive, are especially suitable for use by right-handed persons. It is within the purview of the invention, however, to provide a modified form of the comb for use by either a right-handed or a left-handed person. To this end, the comb is formed of a plastic or equivalent material having a substantially-solid back-portion 31 and an integral handle 32, the back-portion being provided with curved teeth indicated generally at 33, molded or otherwise formed therewith. In this form of the invention, each tooth 33 comprises a relatively-constricted root-portion 34 joined integrally at its upper end to the bottom edge of the back-portion 31 of the comb; and a pair

60

65

of substantially-symmetrical oppositely-disposed apex-portions 35—35, each tooth as a whole being substantially rocker-shaped, as shown especially well in Fig. 9. The center of curvature of the rocker-shaped teeth is substantially coincident with the center of the back-portion 31 of the comb, while the apex-portions of each tooth are formed on the arcs of relatively-small circles such as to have high degrees of curvature like those of the teeth of the comb 25 shown in Figs. 6 and 7, for successfully lifting and thereby exercising the roots of relatively-thick hair.

By forming the comb with substantially-symmetrical oppositely-disposed curved teeth, the comb may be used successfully by either right- or left-handed persons, the curved teeth serving to exercise the hair and scalp and to facilitate the straightening of snarled and matted hair.

Although the curved teeth shown in Figs. 6 and 7 and Figs. 8 and 9 are associated with combs of substantially-solid back and handle construction, it will be understood that the teeth of this curvature and configuration may be used in conjunction with a comb having a hollow back and handle and the wick construction of the comb of Figs. 1 through 5, for treating the hair and scalp with a suitable lotion.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

40 A comb for treating the hair and scalp, said comb comprising a back-portion; and teeth on said back-portion, each tooth comprising a substantially-straight root-portion and a curved apex-portion which projects laterally therefrom at substantially right angles thereto for lifting the hair from the scalp, the root-portion of each tooth being formed integrally with the back-portion of said comb and arranged in spaced substantially-parallel relationship to the root-portion of an adjacent tooth to provide a slot therebetween for accommodating strands of hair segregated by the root-portions of the teeth in a combing action, the inner edge of the curved apex-portion of each tooth being the arc of a circle and the outer edge of each curved apex-portion being the arc of a circle eccentric to the circle defining the arcuate inner edge of the curved apex-portion of the corresponding tooth.

LAVELLE W. SHIELDS.
